SEPARATOR FOR SELF-PRIMING PUMPS OR
THE LIKE

Harry E. La Bour, Elkhart, Ind.

Application November 5, 1937, Serial No. 172,945

6 Claims. (Cl. 103—113)

My invention relates to centrifugal self-priming pumps and is particularly concerned with the means for releasing the gas entrained in the charge of working liquid during priming.

Self-priming centrifugal pumps usually provide in their structure, or associated structure, means for retaining a charge of working liquid which is employed as a medium for withdrawing air or other gas or vapor from the suction line in sufficient amounts to cause the liquid to rise into the pump.

This charge of liquid, during priming, is involved in three important functions. First, it is charged with air to form a working fluid or mixture within the pump casing. This fluid or mixture has sufficient density to develop the necessary discharge pressure required to permit carrying out of the air in the pump casing and the suction pipe against at least atmospheric pressure, or whatever head the pump may be working against. Second, the charge of liquid provides a pool or body which serves as a reservoir to which the stream of discharged mixture is added and from which the stream of return or priming liquid is withdrawn. Third, the body or pool of liquid permits of the separation of the entrained gas whereby the gas is rejected or eliminated. Additionally, this body or pool of liquid serves as a liquid seal, preventing the entry of air or other gas into the interior of the pump casing.

The effectiveness of the priming action depends upon the balanced relation of the various actions above enumerated. The mixing of the liquid with gas in the pump casing is effected by the rapidly rotating impeller and is rather easily attained because of the positive effect of the impeller.

The separation of the gas from the liquid is usually carried on in a chamber known as a separator, which, during priming, retains the charge or pool of liquid above referred to. If all gas could be eliminated from the return or priming liquid the rate of priming would be greatly enhanced. In fact, the chief practical obstacle to effectiveness in priming is the difficulty of eliminating the entrained gas from the liquid which is returned to the pump casing. This is apparent from the fact that any entrained gas in the return liquid expands upon entering the suction zone in the pump casing.

A further practical difficulty is the necessity for retaining a generous volume of the liquid in the separator to maintain an adequate seal upon the pump passageways, particularly upon

the return passageway. However, the greater the volume of liquid required to be maintained in the separator, the more difficult it is to secure rapid elimination of the entrained gas.

In the early form of pump shown in Patent No. 1,578,236 and wherein the separator is disposed above the pump, gravity separation, i. e., rise of the entrained air by difference in gravity to the releasing surface of the liquid, was chiefly relied upon.

For certain situations, such as low head mine work, the top type separator required too great head room, and I then developed the side type separator, as disclosed in my Patent No. 1,908,635. In this type of separator the liquid in the separator was caused to whirl on a vertical axis by discharging the mixture stream tangentially at the side of the cylindrical separator. In that case the return passageway communicated with the separator at a point below the main discharge passageway. This permitted the employment of a more compact separator, but it has several drawbacks.

Since the work of the separator comprises such an important part of the work of the unit during priming, I have devoted much study to the provision of separators for various designs of pumps, and call attention to separators shown in the following patents issued to me:

In Patents Nos. 1,915,678 and 2,019,143 I applied the principle of separation by centrifugal action in a top type separator, the whirl occurring on a horizontal axis and lying in substantially a vertical plane.

In Patent No. 1,966,896 I combine the action of centrifugal separation with gravity separation in a separator surrounding the pump casing.

In Patent No. 2,005,466 I employed a helical travel of the mixture on a horizontal axis, supplementing the same with gravity separation in a distinct and separate part of the separator.

While these various forms of separator and their separating action gave better separation at least for certain purposes, it is to be observed that they became more complex and more expensive to construct.

The object of the present invention is to provide a separator of simple, inexpensive construction and of good efficiency. The present separator is the first to take an entering vertical flow of mixture, spread it out in a relatively thin stream moving in a horizontal whirl on the inner cylindrical walls, and then more or less retarding or stopping the whirl enough to insure sealing the outlet and causing the liquid to flow down

and out of the separator in a substantially vertical direction.

A further object is to teach a method of separating gas from liquid in a separator particularly adapted for centrifugal pumps of the self-priming class.

A further object is to provide a top type separator for pumps of the class herein referred to, applicable to pumps of present construction to 10 improve the effectiveness of pumps of this class, both in priming and in liquid pumping.

A further object is to provide a separator, for pumps of the type herein referred to, which has the ability to clean itself and avoid clogging with 15 entrained solids. Also, this separator tends to prevent the return of solids from the bottom of the separator into the pump casing during priming or backflow which occurs upon stopping the pump.

20 Other and incidental objects will be apparent from the following detailed specification and the appended claims.

Now in order to acquaint those skilled in the art with the manner of constructing and operating a specific embodiment of my invention I shall describe, in connection with the accompanying drawings, one form in which my invention may be embodied.

In the drawings:

30 Figure 1 is a front elevational view of a separator superimposed upon a part of the pump casing;

Figure 2 is a top plan view of the separator of my invention;

35 Figure 3 is a side view of the separator taken from the right of Figure 1;

Figure 4 is a vertical section taken on the line 4—4 of Figure 3;

40 Figure 5 is a horizontal section taken on the line 5—5 of Figure 4, looking downwardly; and

Figure 6 is a diagrammatic side elevational view illustrating the component parts of a complete self-priming pump.

In the attainment of the above objects I provide 45 a novel method of separation which involves the employment of a body of fluid whirling on a vertical axis to produce inertia separation or centrifugal separation. This vertical whirl is, however, not a free whirlpool, for reasons later to be 50 explained, but a whirl with a certain amount of breaking or retardation, which has the dual effect of preventing too deep a vortex and also of tending to pile up or gather the liquid at the mouth of the return passageways. Thereby the 55 orderly separation and return of priming liquid is assured over a fairly wide variation of operating conditions such as speed, density of the liquid, volume of liquid, vacuum attained during priming, etc.

60 Referring first to Figure 6, I have here shown a self-priming centrifugal pump which comprises the main parts as follows. The pump casing 1 has its inlet at 2 to which there is connected an inlet trap 3 having inlet connection 4. The pump 65 casing 1 has a discharge connection 5 which is illustrated in detail in Figure 1 and this discharge connection is coupled to the separator 6 which has at its upper end the outlet connection 7. The pump casing 1 contains a suitable rotor 70 or impeller provided with vanes 9 which, in this case, sweep the inside periphery of the channel in which the blades 9 run. The inner periphery 10 of the channel, in which the blades 9 run with relatively small clearance, communicates through 75 two tangential passageways 12 and 13 with outlet

openings at the top of the pump casing where the connection 5 is made. The passageway 12 is the main discharge passageway and the passageway 13 is the auxiliary discharge passageway which, during the priming operation, serves as 5 the return passageway for the priming liquid to maintain the circulation of liquid back into the pump casing for discharge of the mixture through the main passageway 12.

The casing 1 and the separator 6 have meeting 10 flanges 14 and 15 for convenience in construction and assemblage of the parts. Obviously, the separator may be cast as an integral part of the back plate of the casing, or the structural arrangements may be otherwise varied without departing from the present teaching.

The separator 6 comprises, in the form shown, a hollow cylindrical body portion providing a separating and discharge chamber. A top outlet connection 7 may be disposed in any horizontal 20 direction desired. Here it is shown as facing forward parallel to the axis of the impeller shaft 16. The outlet connection 7 comprises a tubular passageway 17 formed through a neck 18 and herein shown as surrounded by a clamping flange 19 for 25 making connection with the discharge pipe of the pump, which may be led to any suitable point, preferably to a point communicating with atmosphere. The top of the separator is provided with a threaded opening 21 for filling purposes 30 and this opening 21 is normally closed by a screw plug 20 shown in dotted lines in Fig. 1.

The lower end of the cylindrical body portion of the separator 6 merges into a conical wall 22 and at the central part of the conical section 22 35 is provided the passageway 23 matching with the main discharge passageway 12 in the pump body. A tubular extension 24 contains a return passageway 25 which matches with the auxiliary discharge passageway 13 in the pump body. These 40 passageways 23 and 25 form openings through the mating flange 15 so that when the flanges 14 and 15 are clamped together the separator 6 communicates with the interior of the pump casing through the main discharge passageway 12, 45 23 and the auxiliary discharge passageway 13, 25. Obviously, any of these parts may be formed as separate pieces joined together for convenience in manufacture and assembly.

Within the separator 6 there is formed an 50 integral inclined vane 27 which defines a passageway 28 forming a communication between the opening 23 and the interior of the separator 6. This inclined vane has its lower edge joined to the conical portion 22 along the curved intersection 29 indicated in Figs. 2 and 3 in dotted lines. The edge of the vane 27 indicated by the intersection of the vane with the cylindrical portion is designated by reference numeral 30. The free edge of this vane is indicated by reference 55 numeral 32. This vane may be flat, that is, planar form, or it may be warped, as desired. Its function is to impart a tangential direction to the mixture entering through the central opening 23 under the vane 27. In other words, 60 the liquid discharged through the main discharge passageway 12 enters through the opening 23 in the bottom of the separator and is directed by the vane 27 in a spiral and subsequent helical path around the inside periphery of the separator 6. Thus the axial entry is directed into tangential travel.

This tangential travel inside of the circular chamber would tend to form a whirlpool with a deep vortex at the center. Depending upon the 75

velocity of discharge and the quantity of liquid forming the charge of priming medium, the vortex might extend down far enough to produce a relatively thin layer of liquid over the opening 33 (see Figure 5) where the return passageway 25 opens into the interior of the chamber 6. Hence, under certain conditions, particularly where a relatively high suction is being created inside the pump casing, a tendency is produced for the atmospheric pressure suddenly to strike through the relatively thin layer of liquid and travel down through the opening 33, passageways 25 and 13, into the interior of the pump casing, destroying the vacuum. The whirling motion of the liquid to free the same of the entrained air is highly desirable, as it performs two useful functions, first, the centrifugal effect of forcing the air to the center of the whirlpool and second, giving a greater area of free surface from which the gas can escape from the liquid. However, an uncontrolled vortex is undesirable for the reasons above stated.

A vertical rib or baffle 34 extends approximately radially from the inner wall of the separator 6 in a vertical direction. This baffle or rib performs two useful functions. The first is to create a region of pressure of liquid, by impingement of the liquid stream thereagainst, directly over the opening 33. That is to say, considering the direction of rotation of liquid charged with air in the separator, the tendency of the lighter liquid mixture is to go to the top, and the denser or less gas-containing liquid to gravitate toward the bottom of the separator, but the tangential motion imparted by the vane 27 causes both parts of the liquid to move in substantially a helical or spiral path. This motion of the liquid represents a certain kinetic energy which, by impingement against the vane 34, is transformed into pressure upon the mouth 33. This insures sealing of the opening 33 with liquid and also performs the useful function of putting a braking or amortizing effect upon the otherwise uncontrolled whirling of the liquid. The form of this vane or baffle 34 may be controlled to produce the desired effects above indicated, or either of them.

It will be seen in Figure 5, as indicated by the arrow 36, that the spiral and helical flow produces an impingement upon the side of the rib or baffle 34 which is adjacent the opening 33, whereby to create pressure at this point. The liquid not so engaging the vane or baffle 34 is forced radially inwardly in order to continue its rotary travel. By this arrangement a control of the vortex action is secured and even if the retained priming liquid is below normal, as sometimes occurs, the piling up or impingement against the vane 34 and consequent sealing of the port 33 is an important aspect of the present invention. Also, it may be seen that the pump may be designed to prime on a smaller charge of liquid under these conditions.

The operation of the pump, in brief, is as follows:

Assuming that the pump has ceased pumping liquid, and liquid has been allowed to flow back through the connection 7, separator 6, pump casing 1, through the trap 3 and back through the suction connection 4 to the point of breaking the suction existing at the top of the trap, a certain charge of liquid will be retained in the trap and in the pump casing. This, as a maximum, is represented by the level A—A which is the bottom of the suction connection 4. As-

suming that the suction pipe is sealed with water and that the shaft 16 is rotated, liquid will be drawn from the intake trap 3 and discharged through both passageways 12 and 13 and driven into the separator 6. Immediately thereafter, since the impeller cannot develop sufficient pressure on air alone, liquid will return through the port 33, passageway 25 and 13, into engagement with the impeller 8, whereupon a mixture of gas and liquid is formed of a density great enough to create a discharge pressure to prevent return of liquid through the passageway 12. The pump then continues to circulate the priming liquid, driving mixture out through the passageway 12 and receiving priming liquid back through the passageway 13. The stream of discharge mixture passes up through the central passageway 23 in the bottom of the separator 6, under the vane 21, where it is directed in a spiral path as indicated in Figures 4 and 5, giving to the body or pool of liquid in the chamber 6 a whirling motion, the whirl being on a vertical axis. This creates a desirable separating action for separating the gas from the liquid, due both to the centrifugal effect and to the increase of area, as well as the thinning of the layer of liquid, that is, reducing the distance which a bubble of gas must travel in order to reach a surface where it can free itself. The uncontrolled whirling of the liquid is prevented by the baffle 34, which creates a plenum by impact of the liquid upon the port 33. The liquid piles up along the rib or baffle 34 and tends to fall into the port 33, where it flows back by way of the passageway 25, 13 to maintain the circulation of the pump during priming. When the priming operation has proceeded to the point of drawing liquid from the source in through the intake trap 3 into the pump chamber 1 to fill or substantially fill the impeller 8, the pressure developed upon the secondary or return passage or throat 13 is great enough to prevent the return flow of liquid through this route and liquid is discharged through both 12 and 13 into the separating chamber in the separator 6. Due to the action of the vane or baffle 34 in braking or amortizing the whirl, and due to the outflow of liquid at the port 33 as distinguished from the previous inflow, a greater braking action or amortization of the whirl is produced by the flow of the secondary passageway, whereby the losses which otherwise would occur due to the whirling action or eddying is reduced when the two throats are discharging liquid. The vane or baffle 34 may be inclined in a direction opposite to the whirl created by the main discharge stream so that the two effects can be caused even more to counteract each other. This is a refinement, and is optional. When the pump thus pumps liquid the separator 6 fills with the liquid and discharge occurs at the opening 17 in the discharge connection 7.

Since the member 6 which I have above termed the separator chamber serves the dual function of a separator chamber during priming and a means for joining the two discharges from the throats 12 and 13 during liquid pumping, it can be seen that it performs an important function in the operation of a self-priming pump unit. In other words, the action of the impeller and its casing 1, in conjunction with the action occurring in the separator 6 during priming and during liquid pumping, involves an important cooperation, each being influenced by the operation of the other.

I do not intend to be limited to the specific details shown and described, as the above specific embodiment is given by way of example and illustration, rather than of limitation.

5. I claim:

1. For use as a part of a self-priming centrifugal pump, a separator comprising a tanklike substantially vertical cylindrical shell having a top outlet to permit the escape of gas during priming and for the discharge of liquid after priming is completed, a vertical inlet at the lower end of said shell, a vane in said shell for causing the vertically entering stream of mixture to travel about the inner periphery of the shell in a horizontal loop, an outlet for the flow of priming liquid from the separator back to the pump, and a baffle disposed in relation to the latter outlet to cause a piling up of the whirling liquid at said latter outlet to seal the same with liquid during priming.
2. A separator and discharge chamber for a self-priming centrifugal pump comprising a substantially cylindrical shell having a main outlet connection at its upper end for the discharge of gas during priming and the discharge of liquid during liquid pumping, said shell being disposed with its longitudinal axis substantially vertical, inlet means at the lower end of the shell arranged to direct an entering stream of mixture during priming substantially tangentially to the inner periphery of said shell to produce a horizontal swirling of the mixture in the chamber, an auxiliary passageway in the lower end of the chamber and a baffle adjacent said auxiliary passageway extending in a direction transverse to the direction of swirl of the liquid, said baffle being adapted to be engaged by the swirling liquid and thereby causing the liquid to pile up and seal the auxiliary passageway during priming.
3. A separator and discharge chamber having a vertical axis and an outlet at its upper end, means to discharge a vertically entering stream of mixture of gas and liquid into the separator

in such manner as to produce a horizontally swirling body of the mixture within the chamber, an outlet for liquid from which the gas has been separated and a vertically extending vane behind said outlet with reference to the direction of motion of the swirling body, said vane being adapted to be impinged by the swirling body for creating a liquid seal upon said outlet.

4. A separator for a centrifugal self-priming pump comprising a shell of substantially cylindrical form arranged with its longitudinal axis vertical, an outlet at the upper end, a main inlet disposed substantially axially at the lower end of the shell, and a priming outlet leading from the peripheral part of the lower end of the shell, means for directing the vertically entering stream of mixture substantially tangentially of the inner walls of the shell in a generally horizontal direction and a baffle disposed in a generally vertical direction on the inner wall of the shell adjacent the priming outlet, said baffle tending to insure sealing of said outlet with liquid and limiting the whirling of the liquid within the separator.

5. The separator of claim 4 wherein the lower end of the shell has a conical portion with the main inlet disposed at the apex of the cone and wherein the means for directing the stream of mixture comprises a vane extending from the conical wall to the cylindrical wall of the shell.

6. A separator having a cylindrical shell with a vertical axis, a top outlet, a mixture inlet for leading mixture generally vertically into the shell and having means for directing the same in a thin layer whirling horizontally on the inner cylindrical walls, a vertically disposed baffle on the inner wall of the shell and a generally vertically downwardly directed outlet having an opening into the inside of the shell in front of said baffle with reference to the direction of motion of the whirling layer.

HARRY E. LA BOUR.
